ORGAN CONSOLE

Winsor D. White, Jr., Blowing Rock, N.C., assignor to
D. H. Baldwin Company, Cincinnati, Ohio, a corpora-
tion of Ohio

Filed Oct. 1, 1969, Ser. No. 19,361

Term of patent 14 years

Int. Cl. D17—01

U.S. Cl. D56—2

Fig. 1

FIG. 1 is an angular perspective view of an organ console embodying my new design.

FIG. 2 is a front perspective view thereof.

FIG. 3 is a side elevational view thereof.

The back of the organ console, not shown, is conventional.

I claim:

The ornamental design for an organ console, substantially as shown and described.
